R. LEVINGTON.

Car-Axle Box.

No. 8,428.

Patented Oct. 14, 1851.

UNITED STATES PATENT OFFICE.

ROBERT LEVINGTON, OF MONROE, MICHIGAN.

AXLE-BOX FOR RAILROAD-CARS.

Specification of Letters Patent No. 8,428, dated October 14, 1851.

To all whom it may concern:

Be it known that I, ROBERT LEVINGTON, of Monroe, in the county of Monroe and State of Michigan, have invented a new and useful 5 Improvement in Oil-Boxes for Railroad Carriages, Cars, &c.; and I do hereby declare that the following is a full, clear, and exact description of the same, reference being had to the accompanying drawing, in 10 which—

Figure 1, is an isometrical view; Fig. 2, a transverse and Fig. 3, a longitudinal section, in each of which, where the same parts are shown they are designated by the same letters of reference.

The nature of my invention consists in providing a sliding partition in the lower part of the box which is operated upon by a screw, whereby the packing is compressed 20 against the back, sides, and bottom of the box, (which inclines upward) and also, the underside of the journal—keeping the journal in close contact with the composition box and compressing the packing closely against 25 the inner end of the box and shoulder of the journal, so that the oil cannot escape and at the same time, forming a reservoir for oil in front whereby a constant supply of oil to the journal through the medium of the pack- 30 ing is attained without the usual and otherwise unavoidable waste of oil.

(a, a) is the frame of the box which is provided with a lid which is secured by bolts (b, b,) passing through it and screwing 35 into projecting lips. The journal of the axle (c,) is cut down leaving a shoulder and also a flange on its end between which the composition box (d) rests. Sliding horizontally in the bottom of the box on guides 40 or ways is a vertical partition (e) its upper side conformable to the axle, but not fitting it close but so as to leave space enough to allow the oil to flow into the packing. This partition (e) is for the purpose of pressing 45 together the packing against the axle so as to prevent the escape of oil at the back of the box, but at the same time allowing the oil to penetrate to the packing and supply the required quantity to the axle. It is 50 forced against the packing by means of a

screw (f) the head of which extends outside of the front or back end of the box so as to be operated upon by a wrench at pleasure, to tighten or slacken the packing; it is nicely fitted to its thread in the end of the box to prevent the escape of oil, but loosely in the partition so as to turn freely therein, and at the same time, slide the partition forward or back as required. The end of the journal terminates within the box 60 leaving considerable space forming a reservoir to contain oil; and it is provided with an aperture (g,) to replenish it with oil, which has projecting from it two metal lips (h h) for the purpose of protecting the cork 65 from accident and at the same time exposing enough of the cork to be readily removed with the finger and thumb.

The space in the box behind the partition grows smaller toward the inner end of the 70 box, by the bottom of the box inclining upward, in order, that the packing may be more compressed at the inner end of the space than at the partition, so as to prevent the escape of oil around the axle, and at the 75 same time, insure a constant supply of oil to the journal by the packing being less condensed at the partition and consequently will absorb the oil there, more readily and lubricate the journal thoroughly. 80

Having thus fully described my improved oil box what I claim therein as new and desire to secure by Letters Patent, is—

The sliding partition (e) operated upon by a screw, or its equivalent, in combination 85 with the inclined bottom at the inner end of the packing space, condensing the packing more at the inner end of the packing space than at the partition, whereby the oil is prevented from escaping, as well, as insuring a 90 constant supply of oil to the journal substantially as herein set forth.

In testimony whereof he has hereunto signed his name before two subscribing witnesses.

ROBERT LEVINGTON.
